Franklin Rudolph

By: Mandy, Black & Feltz Atty:

UNITED STATES PATENT OFFICE.

FRANKLIN RUDOLPH, OF CHICAGO, ILLINOIS, ASSIGNOR TO AMERICAN CAN COMPANY,
OF NEW YORK, N. Y., A CORPORATION OF NEW JERSEY.

CAN-BODY BLANK.

Application filed September 1, 1922. Serial No. 585,602.

My invention relates to an improvement in the formation of blanks for can bodies and has for a principal object the provision of a blank which, when formed into a can body and the latter flanged in the usual manner preparatory to the double seaming of an end thereto, will present a line defining the overlapping edge in the body flange which will not be likely to sever or damage the gasket which is forced upon said flange in the process of double seaming.

The customary form of blank is such that when the ends thereof are joined in a side seam with the top and bottom edges merely overlapped and flanged, a straight line, radial to the center of the can body, defining the overlapping edge across the flange results, in which case the gasket (when applied on to the can body flange) is cut straight across by said end line of the flange. With this construction, it has been a frequent experience to have the gasket, which is disposed in the flange of the cover, severed by this straight line edge and it is obvious that the effectiveness of the gasket is thus impaired.

In accordance with my invention, the blank is cut so that the line defining this overlapping edge is diagonal, or at an angle to the axis of the flange, and is thus arranged partially in the circumferential form of the gasket whereby damage to said gasket, which results from the straight overlapping line, is, in large measure, eliminated, and the gasket is permitted to pack in about the blank edge in the flange.

It is also an object of the invention to provide, in the manner stated, a body flange which offers less resistance to bending in the flanging and double seaming processes and which obtains a finished seam of more even and perfect character.

Other objects and advantages of the invention will be apparent as it is better understood from the following description, which, taken in connection with the accompanying drawings, discloses a preferred embodiment thereof.

Referring to the drawings, Figure 1 is a perspective of a can body formed from a body blank, in which my invention is embodied, prior to the flanging of the ends thereof;

Fig. 2 is a plan view of a blank;

Fig. 3 is a detail perspective, showing the body end flange; and

Fig. 4 is a plan view of said flange showing the line of the overlapping edge.

For the purpose of illustrating the invention, I have shown on the drawings a body blank 11, which may be of tin plate and which is notched at its ends to permit formation of a can body adapted to have ends applied thereto by the usual double seaming process. The arrangement for this purpose, contemplates interlocking of the edges 12 and 13 to form a locked side seam 14 extending throughout the major part of the height of the body. Near the top and bottom edges, the blank is notched at one end at 15 and 16 and cut away at the opposite end at 17 and 18 so that the edge parts 12 and 13 may be flanged and folded into interlocking engagement, leaving end portions 19 and 21 which merely overlap the opposed portions of the opposite end of the blank, being secured thereto, in accordance with the usual method, by solder which is applied to the finished seam.

The purpose of this arrangement is to permit the top and bottom of the can body to be flanged outwardly, as indicated in Fig. 3, it being understood that the can ends are provided with flanges adapted to be interfolded with the flange 22 for closing the container by a double seaming process.

In accordance with my invention, the corners of the blank are cut off at 23 and 24, so that when the parts 19 and 21 are overlapped, as indicated in Fig. 1, and the end of the body flanged, as shown in Fig. 3, the line formed by the cut 24 will be at an angle to the axis of the flange, as illustrated. The opposite corners 25 and 26 are also cut away, to prevent their projecting on the under side of the flange. The diagonal line between said overlapping edges thus extends partially about the circumferential gasket and the latter is less likely to be severed in the process of application, as would result from a straight line across the flange coincident with the axis thereof.

Furthermore, this formation of the blank provides less metal in the flange at the joint than in the type of blank previously employed, and thus offers less resistance to bending of the flange to form the double seam.

It is thought that the invention and many of its attendant advantages will be understood from the foregoing description, and it will be apparent that various changes 5 may be made in the form, construction and arrangement of the parts without departing from the spirit and scope of the invention, or sacrificing all of its material advantages, the form hereinbefore described being merely 10 a preferred embodiment thereof.

I claim:

1. A can body blank, comprising a piece of sheet metal notched in its side edges adjacent the top and bottom to provide interlocking side flanges throughout the major 15 part of the height of the blank and overlapping edges at the top and bottom, the material of the blank at the corner which is disposed inside of the can being cut off diagonally 20 whereby when the can body is flanged outwardly at its ends the overlapping corner edge extends diagonally across above the underlapped flange to prevent severing of a gasket placed thereon when a cover is applied to the can.
2. A can body blank, comprising a piece of sheet metal notched at its corners to permit formation of a can body having an interlocked side seam throughout the major 25 part of its vertical height and having top

and bottom edges which are merely overlapped and not locked, the corners of both the overlapping and the underlapping edges being cut off at an angle whereby when the end of the body is flanged outwardly a reduced amount of metal is present in the flange and less resistance offered to the bending thereof.

3. A can body blank, comprising a sheet of tin plate adapted to be joined at its edges 40 to form a can body with the top and bottom edges in merely overlapping relationship, a corner of the underlapping edge of said blank being cut off diagonally whereby when an end of the formed body is flanged outwardly a diagonal line defining the overlapping edge is presented to the gasket which is forced upon the flange in the process of applying a cover.

4. A can body, comprising a sheet metal blank having its ends interlocked in a side seam throughout the greater part of their height and being merely overlapped at an end of the body, said end being flanged to permit a cover to be secured thereto and the overlapping edge on the top of the flange being cut at an angle to prevent severing of the gasket forced thereon when a cover is applied.

FRANKLIN RUDOLPH.
